UNITED STATES PATENT OFFICE.

WILLIAM J. FLEISCHAUER AND HERBERT RICHARDSON, OF PONTIAC, MICHIGAN.

DESIGN FOR A HAMMER-HEAD.

45,690.

Specification for Design.

Patented Apr. 28, 1914.

Application filed January 2, 1914. Serial No. 810,078. Term of patent 7 years.

To all whom it may concern:

Be it known that we, WILLIAM J. FLEISCHAUER and HERBERT RICHARDSON, citizens of the United States, residing in Pontiac, in the county of Oakland and State of Michigan, have invented a new, original, and ornamental design for a Hammer-Head, of which the following is a specification, reference being had to the accompanying drawing, forming part thereof.

The figure is a perspective view of a hammer head showing our design.

We claim:

The ornamental design for a hammer head as shown.
